MECHANISM FOR MAKING TINSEL FABRIC

Harry Rubinstein, Brooklyn, N. Y.

Application August 2, 1935, Serial No. 34,440

12 Claims. (Cl. 66—125)

The invention relates to the manufacture of knitted fabrics of the novelty type particularly adapted for millinery and other purposes, and embodying tinsel.

5 In knitting fabrics of this type it has been customary to make use of tinsel thread comprising a cotton or other core about which the tinsel is helically wound. This particular material is imported and is expensive, the result being that 10 such novelty fabrics are excessively costly to produce.

It is with the above facts in view that I have devised the present invention which contemplates an attachment for an ordinary circular type 15 spring needle knitting machine whereby domestic inexpensive tinsel in the form of a plain flat or untwisted narrow strip may be successfully used by laying it in with the threads of a knitted fabric. It has heretofore been difficult to use 20 the plain tinsel, one trouble being the necessity for winding it off from the spools on which it is supplied to the trade and onto the bobbins of the knitting machine, and another objection being that during said winding there is considerable 25 danger of twisting the tinsel with the result that it is very easily broken.

An important object of my invention is therefore to provide an attachment for a knitting machine to take the place of as many bobbins as 30 may be desired, depending upon the design of the fabric, and by means of which the tinsel carrying spools may be supported and the tinsel unwound directly therefrom and laid into the fabric without being previously wound onto the standard 35 type of bobbins with which such knitting machines are equipped.

Another important object is to provide a novel method of making such tinsel fabric involving simply laying in the tinsel in contradistinction 40 to knitting it in so that the resultant fabric will not be objectionably heavy and so that the tinsel will not come clear through to the reverse side and will therefore be prevented from contacting the skin of a wearer.

45 A more specific object is to provide tinsel spool holding means adapted to rest gravitationally upon the rods commonly provided at the top of a knitting machine, the spool holder being, moreover, of such construction that a spool may be quickly and easily changed.

An additional object is to provide mechanism 50 of this character which will be simple and inexpensive to make, convenient to use, efficient and time saving, and a general improvement in the art.

To the attainment of the foregoing and other objects and advantages, the invention preferably consists in the detailed construction and the method steps to be hereinafter more fully described and claimed and illustrated in the accompanying drawings in which:

Figure 1 is a fragmentary perspective view illustrating one form of spool holder constructed in accordance with the invention.

10

Figure 2 is a top plan view thereof,

Figure 3 is an elevation,

Figure 4 is a detail section on the line 4—4 of Figure 3,

15

Figure 5 is a side elevation of a simplified form of the device,

Figure 6 is a section taken on the line 6—6 of Figure 5,

15

Figure 7 is a bottom plan view,

Figure 8 is a detail perspective view showing one end of the adjusting bolt,

20

Figure 9 is a front elevation of yet another modification,

20

Figure 10 is a section taken on the line 10—10 of Figure 9,

Figure 11 is an enlarged expanded elevation 25 showing a fragment of one pattern of fabric which can be produced by my invention,

Figure 12 is a sectional view therethrough.

Referring more particularly to the drawings the numeral 15 designates a pair of the supporting rods provided upon the top of a well known type of circular knitting machine for instance

30

the standard variety put out by The Wildman Manufacturing Company of Norristown, Pennsylvania, though the invention is not necessarily limited to this specific machine. The numeral 16 indicates a portion of the common stop motion.

35

Other details of the machine are unnecessary to a proper understanding of the present invention and are therefore neither shown nor described.

40

In carrying out the form of the invention disclosed in Figures 1 to 4, I provide an inverted U-shaped yoke 17 having parallel resilient arms 18 and equipped at its bight portion with an inverted U-shaped frame 19 secured in place in any convenient manner as for instance by screws

45

20. Located between the free end portions of the resilient arms 18 is a spindle 21 having tapered ends 22 journaled through small holes 50 in the arms. This spindle is provided at one end with a fixed sleeve 23 and at its other end with a slidable collar 24 adapted to be held in adjusted position lengthwise of the spindle as by a set screw 25. The sleeve 23 and collar 24 are 55

formed with tapered portions 26 arranged in confronting relation and adapted to engage within the ends of a spool 27 carrying tinsel 28 which, in accordance with my invention, is simply a flat strip of thin metal of greater width than thickness in contradistinction to a thread circular in cross section such for instance as the imported variety which consists of a cotton or other thread core wrapped with tinsel.

10 Tinsel of the type that I use is supplied to the trade on two sizes of spools, one being wooden and the other metal. The adjustability of the collar 24 along the spindle 21 takes care of the two sizes and types of spools. The spindle is 15 clamped between the arms 18 by virtue of the fact that the arms 18 are urged toward each other and into engagement with the pointed ends 22 of the spindle by a set screw 29 which is threaded through one arm of the frame 19 and 20 which engages the adjacent arm 18 for urging it inwardly or flexing it.

The device is used by placing it at the desired location with the bight of the yoke engaging upon the pair of rods 15. This position may be maintained and the device prevented from moving about by means of a pair of elongated curved springs 30 secured as at 31 upon the confronting faces of the arms 18 and having outwardly divergent free ends 32 bearing upwardly against the 30 rods. The tinsel 28 is threaded through the stop motion device 16 and led into the machine. It need hardly be mentioned that this stop motion device is one of the ordinary variety provided for the purpose of stopping the machine in the event 35 of breaking of a thread. The number of spool holding devices and their location with respect to the knitting stations depends of course upon the pattern of the fabric desired to be made. The cams and other elements of the machine, not 40 shown, are so adjusted that the tinsel is not knitted but is simply laid or floated into the fabric. The advantage of this is that the weight of the finished fabric is kept as low as possible and the tinsel is prevented from extending through to 45 the reverse side, thereby avoiding its contacting with the skin of the wearer. While a wide variety of patterns may be produced, Figures 11 and 12 show, respectively, an enlarged expanded elevation of a fabric and a sectional view through 50 the same. It is intended that the tinsel be laid in with very little tension on it so that it will appear upon one side of the fabric and in raised loose relation thereto, that is to say such is the case with the particular fabric shown though it 55 should be understood that this is not limitative but is on the contrary simply illustrative.

It is not necessary to employ the identical structure shown in Figures 1 to 4 inclusive as in Figures 5 to 8, I have disclosed a simplified form 60 of spool holder which operates very efficiently and which might in some respects, on account of its simplicity, be considered a preferred form of the invention. Referring to these figures the holder is shown as comprising an inverted generally U-shaped yoke 33 having inwardly offset resilient arms 34 carrying supporting members 35 with tapered ends 36 adapted to engage within the ends of a spool and to be held therein by virtue of the provision of a bolt 37 traversing the 70 yoke having at its head end flattened sides 38 located within a keyhole slot 39, which permits detachment, and having at its other end a wing nut 40. This form of the device is supported upon the rods 15 and used in identically the same manner as the first described one but has the advan-

tage of consisting of fewer parts and therefore costing less to manufacture.

The invention is susceptible of further variations and in Figures 9 and 10, I have shown a holder comprising an elongated rectangular block 41 to the ends of which are secured spaced parallel flexible arms 42 carrying at their free ends adjustable pivots or trunnions 43 engageable within recesses in the ends of a spindle 44 having at one end a fixed sleeve 45 and at its other end a slidably collar 46 held in place by a set screw 47. This form of spindle is almost identical with the one shown in the first described form of the invention except for the trunnion arrangement and the members 45 and 46 have tapered portions 48 engaging within the ends of the spool. The spindle is held properly between the arms 42 by virtue of the provision of a set screw 49 threaded through a strip 50 secured to one end of the block 41 outwardly of the arm 42, this set screw being engageable with the arm 42 for holding both arms in proper supporting relation to the spindle. This modification is shown in identically the same manner as the above described ones, the only differences being in the mechanical construction.

From the foregoing description and a study of the drawings it will be apparent that I have thus provided a very simple means whereby the flat ribbon type of tinsel may be successfully and easily used for producing tinsel fabrics and that, moreover, without it being necessary as a preliminary step to wind the tinsel onto the usual bobbins, it being known that such winding twists the tinsel and seriously weakens it. The great advantage in using this flat ribbon or all metal type of tinsel in contradistinction to that type wrapped about a thread core is that actually this plain type of tinsel costs only one-fourth of the other variety which is imported and which is necessarily more expensive. It will therefore be obvious that by the employment of my novel mechanism and method fabric of the tinsel type may be produced more quickly and easily and at a fraction of the cost of that made in the usual way and with the other type of tinsel thread.

While I have shown and described several embodiments of the invention together with one type of fabric, it should be understood that this is entirely for purposes of illustration as the right is reserved to make all such changes as will constitute no departure from the spirit of the invention or the scope of the claims hereunto appended.

Having thus described the invention, I claim:

1. In a knitting machine of the rotary circular type provided at its top with pairs of rods, means for supporting a spool of metallic tinsel of the flat ribbon type having a width greater than its thickness in contradistinction to the type helically wound upon a core, said means comprising a frame gravitationally engageable upon a pair of said rods and having spaced resilient arms, a spindle rotatably journaled between said arms and adapted to carry the spool upon which the tinsel thread is wound, and means for varying the position of the arms with respect to each other.

2. In a knitting machine of the rotary circular type provided at its top with pairs of rods, means for supporting a spool of metallic tinsel of the flat ribbon type having a width greater than its thickness in contradistinction to the type helically wound upon a core, said means comprising a frame gravitationally engageable

upon a pair of said rods and having spaced resilient arms, a spindle rotatably journaled between said arms and adapted to carry the spool upon which the tinsel thread is wound, and screw means for varying the frictional engagement of the arms with the spindle.

3. An attachment for a knitting machine of the rotary circular type provided at its top with pairs of rods, said machine being adapted to 10 knit a conventional fabric consisting of inter-engaged wales or loops in successive rows, said attachment comprising a supporting member gravitationally engageable upon a pair of said rods and having resilient arms, a spindle located between said arms, trunnion means rotatably supporting said spindle with respect to said arms, said spindle being adapted to support a spool upon which is wound a tinsel thread of the flat and untwisted ribbon type, and means 20 for varying the position of said arms with respect to each other.

4. An attachment for a knitting machine of the rotary circular type provided at its top with pairs of rods, said machine being adapted to 25 knit a conventional fabric consisting of inter-engaged wales or loops in successive rows, said attachment comprising a supporting member gravitationally engageable upon a pair of said rods and having resilient arms, a spindle located 30 between said arms, trunnion means rotatably supporting said spindle with respect to said arms, said spindle being adapted to support a spool upon which is wound a tinsel thread of the flat and untwisted ribbon type, and means for varying 35 the position of said arms with respect to each other, said spindle including a member relatively fixed with respect thereto and further including a member slidably adjustable with respect thereto, both of said members having tapered portions engageable with the ends of the spool whereby spools of different lengths may be accommodated.

5. An attachment for a knitting machine of the rotary circular type provided at its top with 45 pairs of rods, said machine being adapted to knit a conventional fabric consisting of inter-engaged wales or loops in successive rows, said attachment comprising an inverted U-shaped supporting member, a resilient U-shaped member located within the confines of said first named U-shaped member, said assembled first and second named members being gravitationally engageable upon a pair of said rods, a spindle located between the arms of said second named 55 U-shaped member, screw means carried by said first named U-shaped member and engageable with the adjacent arm of said second named U-shaped member for varying the frictional engagement of the second named U-shaped member with said spindle.

6. An attachment for a knitting machine of the rotary circular type provided at its top with pairs of rods, said machine being adapted to 60 knit a conventional fabric consisting of inter-engaged wales or loops in successive rows, said attachment comprising an inverted U-shaped supporting member, a resilient U-shaped member located within the confines of said first named U-shaped member, said assembled first 65 and second named members being gravitationally engageable upon a pair of said rods, a spindle located between the arms of said second named U-shaped member, screw means carried by said first named U-shaped member and engageable with the adjacent arm of said second named U-shaped member.

member for varying the frictional engagement of the second named U-shaped member with said spindle, said spindle carrying a fixed conical head and a second conical head longitudinally adjustably mounted thereon.

7. An attachment for a knitting machine of the rotary circular type provided at its top with pairs of rods, said machine being adapted to knit a conventional fabric consisting of interengaged wales or loops in successive rows, said attachment comprising an inverted U-shaped supporting member, a resilient U-shaped member located within the confines of said first named U-shaped member, said assembled first and second named members being gravitationally engageable upon a pair of said rods, a spindle located between the arms of said second named U-shaped member, screw means carried by said first named U-shaped member and engageable with the adjacent arm of said second named U-shaped member for varying the frictional engagement of the second named U-shaped member with said spindle, said spindle including a fixed head with a tapered surface and carrying a longitudinally slidably mounted head having a reversely extending tapered surface.

8. An attachment for a knitting machine of the rotary circular type provided at its top with pairs of rods, said machine being adapted to 30 knit a conventional fabric consisting of interengaged wales or loops in successive rows, said attachment comprising an inverted U-shaped supporting member, a resilient U-shaped member located within the confines of said first named U-shaped member, said assembled first and second named members being gravitationally engageable upon a pair of said rods, a spindle located between the arms of said second named U-shaped member, screw means carried by said first named U-shaped member and engageable with the adjacent arm of said second named U-shaped member for varying the frictional engagement of the second named U-shaped member with said spindle, and means carried by the assembled U-shaped members engaging said rods for maintaining the proper assembled relation with respect thereto.

9. An attachment for a knitting machine of the rotary circular type provided at its top with pairs of rods, said machine being adapted to knit a conventional fabric consisting of interengaged wales or loops in successive rows, said attachment comprising an inverted U-shaped supporting member a resilient U-shaped member located within the confines of said first named U-shaped member, said assembled first and second named members being gravitationally engageable upon a pair of said rods, a spindle located between the arms of said second named U-shaped member, screw means carried by said first named U-shaped member and engageable with the adjacent arm of said second named U-shaped member for varying the frictional engagement of the second named U-shaped member with said spindle, and a pair of leaf springs secured upon the arms of said second named U-shaped member and having angularly deflected free ends bearing against said rods for maintaining the assembled U-shaped members in proper relation with respect to the rods.

10. An attachment for a knitting machine of the rotary circular type provided at its top with pairs of rods, said machine being adapted to knit a conventional fabric consisting of interengaged wales or loops in successive rows, said

- attachment comprising a supporting member gravitationally engageable upon a pair of said rods and having resilient arms, a spindle journaled between said arms, a strip carried by said supporting member and overlying one of said arms, and screw means carried by said strip and engaging the adjacent arm for varying the frictional engagement of the resilient arms with the spindle journaled therebetween.
- 5 11. An attachment for a knitting machine of the rotary circular type provided at its top with pairs of rods, comprising a U-shaped supporting member gravitationally engageable upon a pair of said rods in inverted position, means between the free ends of the arms of said frame for supporting a thread-carrying spool, means for moving said arms relatively to each other, and means
- 10
- 15

secured within the frame and engageable with said rods for maintaining the frame in position with respect to the rods.

12. An attachment for a knitting machine of the rotary circular type provided at its top with pairs of rods, said attachment comprising a substantially U-shaped frame having its bight portion gravitationally engageable upon a pair of said rods, means at the inner faces of the free ends of the arms of the frame for rotatably supporting a thread-carrying spindle, and spring means secured against the inner faces of the arms of the frame and engageable with said rods for maintaining the frame in fixed relation with respect to the rods.

15 HARRY RUBINSTEIN.
